(57) **CLAIM**

The ornamental design for a tubular speaker system, as shown and described.

DESCRIPTION

FIG. 1 is a front elevational view of a tubular speaker system showing our new design;

FIG. 2 is a rear elevational view of a tubular speaker system showing our new design;

FIG. 3 is a right side elevational view of a tubular speaker system showing our new design;

FIG. 4 is a left side elevational view of a tubular speaker system showing our new design;

FIG. 5 is a top plan view of a tubular speaker system showing our new design; and,

FIG. 6 is a bottom plan view of a tubular speaker system showing our new design.

1 Claim, 6 Drawing Sheets

UNITED STATES PATENT AND TRADEMARK OFFICE
Certificate

Patent No. D555,636 S

Patented: November 20, 2007

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Shu Ting Chen, Shenzhen (CN).

Signed and Sealed this Twentieth day of April 2010.

STELLA M. REID
Supervisory Patent Examiner
Art Unit 2912
